UNITED STATES PATENT OFFICE.

CHARLES S. AYRES, OF CLEVELAND, OHIO.

REGISTERING MECHANISM.

1,227,567.

Specification of Letters Patent. Patented May 29, 1917.

Application filed April 15, 1911. Serial No. 621,198.

To all whom it may concern:

Be it known that I, CHARLES S. AYRES, a citizen of the United States, residing at Cleveland, in the county of Cuyahoga and 5 State of Ohio, have invented a certain new and useful Improvement in Registering Mechanism, of which the following is a full, clear, and exact description.

This invention relates to a device for automatically registering the number of persons who may pass a given place in entering an inclosure. The device is of general application, but it is specifically designed to be used in connection with the prepayment 10 street railroad car, and in this connection will automatically register the persons entering the car without let or hindrance on the part of the conductor.

In general, the device comprises one or a 20 pair of swinging arms which are moved by the passenger in passing into the car, a pivoted plate upon which the passenger steps after passing the arms, thereby depressing the plate, which movement of the plate in 25 conjunction with the movement of the arms automatically operates a registering device. This plate is usually placed in the floor of the platform of the car just in advance of the end sill or step which permits entrance 30 to the car inclosure proper. There is also a second plate pivoted upon the end sill or floor of the car-body proper which is placed in line with the first mentioned plate and which is connected thereto by means of levers 35 in such a manner that a person stepping upon the second plate will raise the first plate, and the ratio between the levers connecting these plates is such that a person of comparatively light weight stepping upon 40 the second plate will cause the movement of the first plate even though a heavy person be standing upon the first mentioned plate. In this manner, the registration of all persons who step upon the first plate or that 45 one which is pivoted upon the floor of the platform will be effected.

There are sundry details in construction which will appear more at large in the specification and claims, which also enter into the 50 invention.

Generally speaking, the invention comprises the elements and combinations thereof set forth in the accompanying claims.

Reference should be had to the accompa-

nying drawings forming a part of this 55 specification, in which Figure 1 shows in elevation a portion of the body of a car and platform therefor, and showing the installation of the device of this invention; Fig. 2 is a top plan view of the device with 60 certain portions broken away to show the construction; Fig. 3 is a sectional elevation through the device; Fig. 4 is a front elevation of the device with certain portions removed; Fig. 5 is an elevation of certain of 65 the mechanism with certain parts of the mechanism removed to more clearly show the desired elements; Fig. 6 is a perspective view of one of the controlling elements in the mechanism; Fig. 7 is a fragmentary 70 view showing the manner of connection between the cables and the operating arm.

At the present time, most pay-enter cars are equipped with a fare box in which the passenger deposits his fare and the conductor merely registers the fare, makes 75 change and sells tickets.

The fare box affords but a partial solution of the problem involved and is open to several serious objections, one being that the 80 money which is put into the fare box is tied up for the time being and cannot be used for the making of change. A second objection lies in the fact that the registration of the passengers is dependent upon the conductor pulling the register rope, and therefore the register is not a certain indication 85 of the number of passengers who have entered the car.

The device shown in this application by 90 registering every person who passes into the car determines the number of passengers for whose fare the conductor is responsible, and this is done without withdrawing the money 95 from circulation, for in the use of this device, the conductor receives the money from the passengers and thus is always supplied with a quantity of change.

The major part of the mechanism for operating this device is contained within a box 100 1, which is provided with a flange 2 and this box is inserted through an opening in the car platform, which opening is of such a size that the flange 2, which extends all the way around the box, rests upon the floor of 105 the platform, the opening in the floor being set the same as the outline of the box.

At one end, the box is provided with ped-

estals or bases 3 and 3^a, which are each formed with a central opening, the opening being screw-threaded near the upper portion which coöperates with the threaded end of a 5 tubular member 4, as shown in Fig. 3. At its upper end, this tubular member is screw-threaded and is provided with a cap 5 having a beveled upper surface which coöperates with a member 6, the under surface of 10 which is beveled to coöperate with the cap 5. The member 6 is provided with an opening through the center thereof, square or angular in shape, for the purpose of receiving the square or angular head of a rod 7, the 15 rod extending through the cap 5, and at its upper end is provided with a screw threaded projection 8 which coöperates with a cap nut 9, as clearly shown.

Within the casing and beneath the pedestal 20 3 there is an annular member 10 provided with a beveled head which seats within an opening 3^b having beveled sides and formed in the lower wall of the pedestal 3. This member 10 has an annular body and is 25 provided with two annular ribs 11 and 12 which are spaced from each other. The member 10 is formed with a central opening through which the rod 7 extends. The lower end of the rod is provided with means 30 for engaging the member 10 and holding it in place. These means may assume any desired form, preferably being a nut engaging with the screw threaded end of the rod 7, so that sufficient tension may be placed upon 35 the rod 7, that this rod and the parts carried thereby may be secured with sufficient rigidity that there shall not be any play.

The mechanism which has just been described is duplicated upon the other side of 40 the device. That is to say, both pedestals 3 and 3^a carry duplicate mechanisms, as has just been described.

A cable 13 shown in Fig. 2 may be secured upon the annular rib 11 and is connected with a cable 14 which is similarly secured upon the mechanism carried upon the pedestal 3^a. Between the two cables 13 and 14 there are rods 15 and 16 which are connected by a turn buckle 17 for the 50 purpose of varying the tension. There are also cables 18 and 19 which are secured to the annular ribs 12 in the same manner as has been described with respect to the cables 13 and 14, and these cables 18 and 19 are 55 also secured to each other in a manner similar to that which has been described. It will therefore be apparent that the rotation of either rod 7 will cause the rotation of the other.

60 The members 6 are provided with arms 20 and 21 which extend toward each other, as clearly indicated in Fig. 2. These arms by their movement cause the rotation of the rods 7.

65 Upon the under side of the annular rib 12

which is associated with the pedestal 3^a there is a pin 22, and to this pin is secured a spring 23 by means of a link 24. The spring 23 is secured to some relatively immovable body, such for instance as the underside of 70 the floor of the car platform. There is also a rod 25 pivoted upon the pin 22 which rod is connected with the plunger of a dash pot 26, and this dash pot is pivotally secured upon the bracket 27 which is bolted to a side 75 of the casing 1.

It will be apparent that the arms 20 and 21 when moved will cause the flexure of the spring 23, which spring will cause the arms 20, 21 to return to the position shown in 80 Fig. 2, when these arms are released. The dash pot is provided to cushion the return of these arms so that their movement may not be too violent.

The casing 1 is provided with a rib or 85 web 28 which extends across the casing 1, as shown in Fig. 1, and this rib, at its upper portion, is formed with a V-shaped notch 29. A plate 30 is formed with a knife edge upon the depending portion 31 thereof, 90 which knife edge rests in the V-shaped notch 29 and forms a pivot for the plate. This plate 30 extends toward the rear of the box 1 and covers the mechanism which is housed within this box. 95

A plate 300 extends between the pedestals 3 and 3^a and touching the floor in the front, covers the forward portion of the plate 30 at the bend therein to form the depending portion 31. This plate prevents a passenger 100 stumbling over the forward end of the plate 30 and protects the plate from being displaced.

The plate 32 is formed with a depending portion 33 at the rear end thereof, which portion is provided with a knife edge that rests within a V-shaped groove 34 formed in a block 35 which is secured upon the floor 36 of the car body. There is a plate 37 which is secured to the floor 36 and the block 35 110 which partially extends over the depending portion 33 of the plate 32, and is provided to cover the pivoted portion of this plate 32 in order that it may not be displaced. The plate 32 is bent at right angles to form the 115 depending portion 38, and this portion 38 is provided with slots 39 through which extending portions of the plate 30 extend, these slots being of sufficient depth to permit the relative movement of the plates 30 120 and 32 without interference.

Within the casing 1 there is a lever device indicated as a whole at 41 which comprises the side members 42 which are joined by cross pieces 43 and 44. The general 125 shape assumed by this lever mechanism is shown in Fig. 2. At one of their ends, the side pieces 42 are formed with knife edges that rest within the groove 29, as will be seen in Fig. 3, and to permit of this, the 130

depending portion 31 of the plate 30 is notched, as shown at 45 in Fig. 2. At the opposite ends, these members 42 extend through the slots 39 in the plate 32 and co-operate with rollers 46 which are suitably mounted upon the plate 38 to extend across the slots therein. In this manner, a rolling contact is produced between the lever mechanism 41 and the plate 32.

10 A second lever, indicated as a whole at 47, is provided with side pieces 48 which are joined together by a cross member 49. At one of their ends, the side pieces 48 are pivoted upon a pin 50 which extends 15 through openings formed in the side members 42 of the lever mechanism 41 and is secured to these side members 42 in any desired manner. The opposite ends of the side pieces 48 are turned upwardly as indicated 20 at 51 in Fig. 3, and bear against the underside of the plate 30. The underside of the member 49 which joins the side pieces 48 is formed with a knife edge, as indicated at 25 54 and is pivoted in a notch formed upon a stationary member 55.

From the mechanism thus described, it will be clear that as a weight is placed upon the plate 32, it will depress that end of the lever mechanism 41 which co-operates with 30 the plate 32, and this depression will lower the point at which the lever mechanism 47 is pivoted upon the lever mechanism 41, and inasmuch as the knife edge 54 co-operates with a stationary member 55 to form a fixed 35 fulcrum, the ends 51 of the lever mechanism 47 will be raised and thus throw the plate 30 upward, if it be depressed. The length of the lever arms for the lever mechanism 41 and 47 may be proportioned as desired, and it is the intention to so proportion 40 these lever arms that a minimum weight when upon the plate 32 will cause the elevation of the plate 30, even when a passenger of maximum weight is standing 45 thereon, and it will be clear that when the plate 32 is vacated, then the plate 30 may move downward and accomplish the registration of the person standing thereon in a manner later described.

50 Within the casing 1 there is a bracket or bracing member formed with the members 55, 56, 57, 58, 59, 60, 61, and 62. The members 62 and 55 are joined together and at a point near their juncture, the bracket is secured to a wall of the casing 1, as indicated 55 at 63. The member 56 is secured to the wall of the casing 1, as indicated at 64, the arm 59 is secured to the casing, and the ends of the members 57 and 58 are secured to the 60 casing wall at 66. The arms 57, 58, 59, 60, 61 and 62 converge and meet in an annular boss 67 shown in dotted lines in Fig. 2, and in full lines in Fig. 3.

This boss is provided with a central opening in which is secured a pin 68. Upon the

pin there is loosely mounted a member 69 which is provided with an extension 70. This member 69 is shown in perspective in Fig. 6 and is provided with a groove 71 occupying a portion of the side between the 70 top and the bottom, and a groove 72 which is below the center of the member and extends to the bottom. These two grooves 71 and 72 meet in a common groove 73 which extends in the same direction as the axis of 75 the member 69. The forward upper edge of the groove 72 is beveled, as indicated at 74 for a purpose later to be described.

The space between the members 57 and 58 of the bracket heretofore described is occupied by a lever 75 which is pivoted upon a pintle 76 that extends through openings in the members 57 and 58. This lever 75 normally extends into the opening or groove 73 of the member 69 and is provided at the end 85 which projects within the groove 73 with a bevel shoulder 77.

This beveled shoulder is adapted to engage the beveled shoulder 74 when the member 69 is turned, as will be later described. 90

There is a member 78 which is secured to the members 56, 57, and 58 of the bracket heretofore described by means of screws or in any other desired manner, as clearly shown in Fig. 2 and in Fig. 3. This member 95 78 is provided with an opening through which extends a movable pin 79, which pin is provided with a head 80 that normally contacts with the underside of the plate 30. At its lower end, the pin 79 rests upon the 100 lever 75 at a point near the end thereof. It will be apparent therefore that as the plate 30 is depressed, the pin 79 will communicate this motion to the lever 75 and cause the end which is associated with the member 105 69 to be raised.

This same member 78 supports a regulating screw 81 which may be raised or lowered to vary the extent of movement of the 110 plate 30.

A bell crank lever 82 is journaled in a suitable manner, as indicated at 83 upon the interior wall of the casing 1 and is provided with arms 84 and 85. The arm 84 is bifurcated and bears upon the top of the member 69 upon opposite sides of the pin 68. The arm 85 is secured to a link 86 which may be flexible or otherwise, and this link is connected with any suitable registering mechanism, as shown. It will be clear that 115 120 as the member 69 is raised, the bell crank lever 82 will be moved, which will cause the movement of the link 86 and the operation of the registering mechanism.

Upon the underside of the annular rib 12 125 which is carried by the member 10 there is a pin 87 which is out of line with the axis of the member 10. Pivoted upon this pin is a link 88 which is hingedly connected at 89 with another link 90. This link 90 is con- 130

5 nected with still another link 91 and the last named link is pivoted upon a pin 92, which occupies an opening in the under side of the extension 70, upon the member 69. The links 90 and 91 may be adjusted with respect to each other so as to take up any lost motion.

10 The operation of the mechanism thus far described is as follows: When either or both of the arms 20 and 21 are moved by a passenger passing between the posts 4 to enter the car, the links 88, 90 and 91 are operated in a manner to turn the member 69 so that the end of the lever 75 enters a groove 72 15 and this groove is of such a depth that when the member 69 is thus turned, the lever 75 will be substantially in contact with the top portion of the groove 72. Then, as the passenger steps forward upon the plate 30, 20 the pin 79 is depressed which raises the end of the lever 75, coöperating with the member 69, and inasmuch as the lever 75 is occupying the groove 72, the member 69 will be raised, thereby moving the bell crank 25 lever 82 and causing the link 86 to be moved to operate the register.

30 As soon as the passenger steps from the plate 30 to the plate 32, this latter plate is depressed and by the lever mechanism heretofore described, the plate 30 is raised, and as before stated, the lever mechanism is so proportioned that even though a second passenger immediately steps upon the plate 30 after the first one has stepped off of it, 35 nevertheless the plate 30 will be raised by the weight of the passenger on the plate 32 and not until the passenger has stepped from that plate, will the plate 30 be depressed to register.

40 If the passengers are attempting to crowd past the gates or arms 20 and 21 too fast, it is desirable that a means be provided for temporarily locking these gates, and this is accomplished through the following mechanism. The annular rib 11 upon the member 10 is notched, as indicated at 93, and co-operating with these notches is a bolt 94 which extends through an opening in the rib 28 of the casing 1, and through an opening 50 in the bracket 95, which is secured to the casing 1, as shown in Fig. 2. Around this bolt 94 is a spring 96 which is arranged so as to normally throw the bolt forward to occupy an indentation 93. The indentations 55 and bolt are so arranged that when the bolt occupies one of the depressions 93, it locks the arms 20 and 21 against movement inwardly, but permits them to move outwardly. The bolt is secured to a link 97 60 which is pivoted upon one arm 98 of a bell crank lever. Another arm 99 is connected with a rod 100 which is suitably connected with a foot lever 101 which is pivoted upon the floor of the platform or the floor of the 65 car according to the place in which the con-

ductor is stationed. The arms 98 and 99 of the bell crank lever are joined by an arm 100, and the bell crank lever is pivoted at the place where the arms 98 and 99 are joined. The pivot upon which these arms move is secured upon the arm 62 of the bracket heretofore mentioned.

70 In practice, the conductor keeps his foot upon the lever 101 and thus permits the passengers to pass between the arms 20 and 21. 75 If, however, the passengers are coming too fast, he may by releasing his foot, lock the arms 20 and 21 and thus prevent the passengers passing onto the plate 30.

80 It is very desirable, if not absolutely necessary, that the devices be unaffected if a passenger should step onto the plate 30 from the plate 32. Such a condition may arise by a passenger stepping backward from the plate 32 to the plate 30, or in case 85 of the necessity for a hurried exit from the car, it may be necessary to have all means of exit unobstructed, and of course it is absolutely necessary that there be no registration under either circumstance which has 90 just been named.

95 If then a passenger were to step upon the plate 30 from the plate 32, the pin 79 would be depressed and the lever 75 would be elevated within the slot 73. If then, the passenger were to again step onto the plate 32, the pin 75 would merely return to its normal position, for by this time, the arms 20, 21 would have returned to their normal position. If, however, after stepping upon the 100 plate 30, the passenger were to continue past the arms 20, 21, the member 69 would be turned, while the pin 75 was elevated, but the member 69 would be turned in a direction opposite to that which it would be 105 turned if a person were swinging the arms 20, 21 inwardly, and this being the case, the pin 75 would enter the groove 71, and the member 69 would not be raised as is the case when the pin 75 enters the groove 72. 110 Therefore, as soon as the person stepping from the plate 30 were to release the arms 20, 21, the lever 75 would return to the groove 73 and drop into place.

115 It is impossible to swing the arms 20, 21 outwardly or away from the plate 30, unless the plate 30 first be depressed,—for if the plate 30 be not raised, the lever 75 remains at the bottom of the vertical groove 73, and inasmuch as an outward movement of the 120 arms 20, 21 causes the rotatable member 69 to turn toward the right as shown in Fig. 6, the lever 75 would strike against the side of the vertical groove 73, when it is attempted to move the arms outwardly. Therefore, for a 125 person entering the car, the arms can move in only one direction.

130 It is evident that various modifications may be made in the structure herein disclosed without departing from the spirit of

the invention, and I consider such modifications within the scope of my invention.

Having thus described my invention, what I claim is:

- 5 1. In a device for registering persons passing a given point, the combination with a registering device, of a pivoted plate member and a movable arm member mounted above the plate member and moving in a substantially horizontal plane, mechanisms operatively connecting the pivoted plate member and the movable arm member with the registering device, said members being successively engaged by the person passing 10 said point, the movement of one of said members setting the said mechanism in position to operate the registering device when the other of said members is operated.
2. In a device for registering persons passing a given point, the combination with a registering device, of a pivoted plate and a swinging arm mounted in front of said plate, said arm and plate being successively engaged by a person passing said point, 15 mechanism operatively connecting the pivoted plate and the swinging arm with the registering device, the movement of the said swinging arm setting the said mechanism in position to operate the registering device 20 when the pivoted plate is operated.
3. In a device for registering persons passing a given point, the combination with a registering device, of a pivoted plate upon which the persons to be registered step, and a swinging arm supported in front of and above the pivoted plate which the said persons must swing before stepping upon the plate, mechanism operatively connecting the pivoted plate and swinging arm with the 25 registering device, the movement of the swinging arm setting the said mechanism in position to operate the registering device when the pivoted member is operated.
4. In a device for registering persons passing a given point, the combination with a registering device, of a pivoted member and a swinging member, said members being adapted to be successively engaged by a person passing said point, mechanism operatively connecting the registering device with the pivoted and swinging members, the movement of the swinging member in one direction and the subsequent depression of the pivoted member causing the registering 30 device to operate, but the depression of the pivoted member in the first instance and subsequent movement of the swinging member being without effect upon the registering device.
5. In a device of the character described, the combination with a registering device, of a pivoted member and a swinging member, a rotatable member, a fixed pivot upon which said rotatable member is mounted and along which it may slide, operative connec-

tion between the rotatable member and a swinging member, mechanism for operating the registering device, said mechanism being in operative position when the rotatable member has been turned by the pivoted member, the said mechanism being operated by the depression of the pivoted member. 70

6. In a device of the character described, the combination with a registering device, of a pivoted member and a swinging member, a rotatable member, a fixed pivot upon which said rotatable member is mounted and along which it may slide, operative connections between the rotatable member and the swinging member, mechanism connecting the swinging member with the registering device operated by the depression of the pivoted member, said mechanism being operative upon the rotatable member when it is turned by the swinging member in one direction, and non-operative when turned in the opposite direction. 75

7. In a device of the character described, the combination with a registering device, of a pivoted plate and a swinging arm, a rotatable member, a fixed pivot upon which said rotatable member is mounted and upon which it may turn and slide, means operatively connecting the arms with the said rotatable member, whereby the rotatable member is turned as the arm is turned, a lever supported upon the fixed pivot, a pin bearing upon one end of said lever and contacting with the said pivoted plate, the other end of said lever coöperating with the aforesaid rotatable member to raise the same 90 when the pivoted plate is depressed, a pivoted lever, one end of which bears upon a face of the aforesaid rotatable member and operative connections between the other end of said lever and the registering device. 95

8. In a device of the character described, the combination with a registering device, of a pivoted plate, and a swinging arm, a rotatable member mounted upon a fixed pivot along which it may slide, operative connections between the said rotatable member and the swinging arm, said member being provided with a vertical groove, and a horizontal groove along the lower side of said member which communicates with the vertical groove, a lever mounted upon a fixed pivot, one end of said lever normally extending into the vertical groove of the rotatable member, operative connections between the other end of said lever and the pivoted plate, whereby the end of the lever within the groove of the rotatable member is raised as the pivoted plate is depressed, a pivoted lever having one end thereof bearing upon the face of the rotatable member, 100 and operative connections between the other end of said lever and the registering device. 105

9. In a device of the character described, the combination with a registering device, of a pivoted plate and a swinging arm, a rota-

- table member mounted upon a fixed pivot along which it may slide, operative connections between said rotatable member and swinging arm, said rotatable member being 5 provided with a groove parallel with its axis in the periphery, a horizontal groove connecting with one end of the said groove, and a second horizontal groove connecting with the first mentioned groove at the other end 10 thereof, a pivoted lever having one end normally extending into the first mentioned groove, means whereby the lever may be raised as the pivoted plate is depressed, the end of said lever being adapted to enter the first horizontal groove upon the rotatable member when the said swinging arm is operated before the plate is depressed, and to enter the second horizontal groove when 15 the plate is depressed before the arm is 20 swung.
10. In a device of the character described, the combination with a registering device, of a pivoted plate, a pair of swinging arms mounted in front of and above the said pivoted plate, said arms extending toward each other, operative connections between the two arms whereby when one of the arms is swung, it will cause the other arm to swing in the same direction, a rotatable member 25 mounted upon a fixed pivot along which it may slide, operative connections between the said arms and the rotatable member, whereby the rotatable member is turned as the arms are swung, a pivoted lever, operative connections between one end of said 30 lever and the pivoted plate whereby the pivoted lever is operated as the plate is depressed, operative connections between the other end of said lever and the said rotatable member, whereby the said rotatable member will be raised when it has been turned due to the swinging of the arms, and operative 35 connections between the said rotatable member and the registering device whereby the registering device may be operated. 40
11. In a registering mechanism, the combination with a registering device, of a pivoted plate, means operatively connecting the pivoted plate with the registering device, a second pivoted plate, said plates being 45 operatively connected whereby the depression of the second mentioned plate causes the first mentioned plate to be raised. 50
12. In a registering mechanism, the combination with a registering device, of a pivoted plate, means operatively connecting the pivoted plate with the registering device, a second pivot plate, lever mechanism operatively connecting with the two plates whereby the depression of the second mentioned plate causes the first mentioned plate to be raised. 55
13. In a registering mechanism, the combination with a registering device, of a pivoted plate, means operatively connecting the pivoted plate with the registering device, a second pivoted plate, a differential lever mechanism operatively connecting the two plates, whereby a heavy weight upon the first plate may be raised by a light weight 60 upon the second plate. 65
14. In a device of the character described, the combination with a registering device, of a pivoted plate, a swinging arm mounted in front of and above the said plate, operative connections between the registering device and the swinging arm and the pivoted plate whereby the registering device will be operated as the arm is swung and the plate depressed, a second plate behind 70 the first pivoted plate, and operative connections between said plates whereby the first plate will be elevated as the second plate is depressed. 75

In testimony whereof, I hereunto affix my 85
signature in the presence of two witnesses.
CHARLES S. AYRES.
